[57] ABSTRACT

A plurality of memory relays have their respective set coils connected in series with and between channel terminals of a first rough setting matrix and a first fine setting matrix, and have their respective reset coils connected in series with and between channel terminals of a second rough setting matrix and a second fine setting matrix. The timing terminals of the first and second rough setting matrices are connected to the output terminals of a rough counting relay and the timing terminals of the first and second fine setting matrixes are connected to the output terminals of a fine counting relay. These counting relays are supplied with clock pulses for counting operation by means of a clock pulse source.

Each memory relay is driven to a set state in response to an output provided at a corresponding channel terminal at a time point preset in the first setting matrixes and is driven to a reset state in response to an output provided at a corresponding channel terminal at a time point preset in the second setting matrixes.

Means for controlling the pulse repetition frequency of the clock pulse and for returning said counting relays and memory relays are provided and frequency control and return operation are controlled advantageously by means of said memory relays.

PROGRAMMING APPARATUS

BACKGROUND OF THE INVENTION

1. Field of the Invention

The present invention relates to an improved programming apparatus and more specifically to such an apparatus for set-driving memory relays in a preset time sequence and then reset-driving the same also in a preset time sequence according to a preset program.

2. Description of the Prior Art

In using machine tools of a type of numerical control, cinema house equipments, neon signs etc. it is required to control a single or a plurality of memory relays in a correct preset time sequence by set-driving the memory relays at a given timing and then reset-driving the same also at a given timing according to the preset program, respectively. A typical example of known apparatus hitherto used for this purpose has a single or a plurality of cams mounted on a common revolving shaft, each cam having a sliding surface in a configuration corresponding to the program set for each channel. Said sliding surface is engaged with electric switching devices such as microswitches, each controlling a corresponding memory relay. A fundamental disadvantage of such devices is that no accurate control in the preset time sequence could be hoped for by the method of setting the program by means of configuration of the cam's sliding surface and also that such a device is liable to be bulky.

In lieu of a combination of the cam having a sliding surface of a programmed configuration and electric switching means engaged therewith, a non-contact type counter such as an electronic counter may be used. However, such non-contact type counter is disadvantageous in that it is expensive, irrespective of the advantage of non-contact.

The same purpose can also be attained with the use of a single matrix contact switching device by, for instance, assigning the group of row contacts to the memory relays in a plurality of channels and the group of column contacts to the timing device or the counting device. When high accuracy is required in respect of time sequence, however, the required number of contacts in the column group is inevitably big and its construction is liable to be highly complicated. Also there are quite a variety of devices proposed for the purpose but none has so far proved satisfactory in respect of accuracy and/or simplicity.

Therefore, it would be advantageous if one may obtain a programming apparatus reasonably simple in construction and capable of performing accurate set-driving and reset-driving. Such a programming apparatus will be all the more advantageous if it is so designed that the speed of the progress of the program can be controlled by the apparatus itself or from outside the apparatus for the desired variegation of the apparatus' functions. Still more advantageous will be such programming apparatus if its functions are further variegated by so designing that return to the starting point can be accomplished according to the program set by the apparatus itself or manually or from outside the apparatus when the program has progressed to a certain timing point.

SUMMARY OF THE INVENTION

Briefly stated, the present invention comprises at

least one memory relay having the set coil energized by an output of a first setting means associated with a counting relay supplied with clock pulses, when counting reaches a preset count, and having the reset coil energized by an output of a second setting means associated with said counting relay, when counting reaches another preset count.

In a preferred embodiment, as the first setting means a first rough setting matrix and a first fine setting matrix are employed and as the second setting means a second rough setting matrix and a second fine setting matrix are employed. The first and second rough setting matrices are supplied with the timing output from a rough counting relay and the first and second fine setting matrices are supplied with the timing output from a fine counting relay. A corresponding plurality of memory relays have their set coils connected in series with and between corresponding channel terminals of the first rough and fine matrixes and have their reset coils connected in series with and between corresponding channel terminals of the second rough and fine matrixes.

Each memory relay is driven to a set state in response to an output provided at a corresponding channel terminal at a time point preset in the first setting matrixes and is driven to a reset state in response to an output provided at a corresponding channel terminal at a time point preset in the second setting matrixes.

Preferably means for controlling the pulse repetition frequency of the clock pulse and for returning said counting relays and memory relays are provided. The frequency control and return operation of these means are advantageously controlled by using the memory relays.

Therefore, an object of the present invention is to provide a simple means which enables easy selection of time sequences to be set.

Another object of the present invention is to provide a means for set-driving a memory relay at the preset timing and then reset-driving the same also at the preset timing.

Still another object of the present invention is to employ a pulse-driven counting relay for determining the timing of the programmed set-driving and reset-driving.

A further object of the present invention is to enable variation of the program progress speed through control of the pulse generation mode by using a pulse-driven counting relay for determining the programmed timing of set-driving and reset-driving.

Still a further object of the present invention is to enable return to the initial state of the whole programming apparatus at a selected timing with the use of a pulse-driven counting relay for determining the programmed timing of set-driving and reset-driving.

It is a further object of the invention to enable various setting of the time sequence with respect to a plurality of channels by a combined connection of at least two counting relays.

It is still a further object of the invention to use at least two counting relays and at least two matrixes annexed thereto respectively for enabling rough setting of timing with one of those and fine setting of timing with the other of those with respect to a plurality of channels.

These and other objects and features of the present invention will become more apparent from the following detailed description when taken in conjunction with the accompanying drawings.

BRIEF DESCRIPTION OF THE DRAWINGS

FIG. 1 is a block diagram showing the basic concept of a programming apparatus in accordance with the present invention.

FIG. 2 is a circuit diagram of the set-driving program setting device used in the apparatus shown in FIG. 1,

FIG. 3 is a circuit diagram of the reset-driving program setting device used in the apparatus shown in FIG. 1,

FIG. 3A is an illustration of a typical memory relay,

FIGS. 4A and 4B are the left half and right half of the circuit diagram of the control system of the apparatus shown in FIG. 1 respectively.

FIG. 5 is a diagram showing the relationship between the set-driving program setting device and the circuit diagram of the control system.

FIG. 6 is a diagram showing the relationship between the reset-driving program setting device and the circuit diagram of the control system.

FIG. 7 is an elevational view of a programming apparatus of an embodiment in accordance with the present invention, and

FIG. 8 is a rear view of the programming apparatus shown in FIG. 7.

DESCRIPTION OF THE PREFERRED EMBODIMENTS

1. An Outline of the Embodiment

FIG. 1 is a block diagram showing the basic concept of the programming apparatus in accordance with the present invention. The programming apparatus as shown basically comprises a pulse source P (generally referring to blocks Man, Ex, Exc, Osc₁ and Osc₂), a counting relay or stepping relay C (generally referring to blocks C₁₀ and C₁), a set-driving setting device M_s (generally referring to blocks MS₁₀ and MS₁), a reset-driving setting device M_r (generally referring to blocks MR₁₀ and MR₁) and a memory relay to be set- or reset-driven Obj (generally referring to blocks S, R and KR).

The pulse source P supplies pulses to the counting relay C and the timing progresses with counting of the pulses. The selected program is set on both setting devices M_r and M_s and as a cooperative function of the progress of said timing and the set program the corresponding driving signals are provided at an output of the set-driving AND gate As and an output of the reset-driving AND gate Ar, respectively, so that individual memory relays Obj are set-driven or reset-driven.

The pulse source is composed of a pulse generator Man, an exterior pulse generator Ex, an exterior-pulse preference control device Exc and two pulse generators Osc₁ and Osc₂ of different frequencies housed in the programming apparatus. Either of generators Osc₁ and Osc₂ is made in an active mode by means of a flip flop FF. This selection may be made by means of a manual switch Msw or the program set on the programming apparatus. Control of the flip flop FF by the set program is accomplished by the output from the AND gates As and Ar which are fed via routes indicated by dotted lines. Outputs from the generators Osc₁ and Osc₂ are fed through OR gate O₂ to an inhibit gate Inh and the output from exterior-pulse preference control device Exc is fed to the inhibit gate Inh so as to inhibit the output from the OR gate O₂. Outputs from the devices Man and Ex and the gate Inh are fed through OR gate O₁ to the counting relay.

The counting relay is composed of a device C₁ for fine counting, for instance, of the unit digit and a device C₁₀ for rough counting, for instance, of the 10th digit, these being connected in series. Similarly the setting devices M_s and M_r comprise devices for fine purpose MS₁ and MR₁ and devices for rough purpose MS₁₀ and MR₁₀ corresponding to the abovementioned devices C₁ and C₁₀, respectively. Coincidence of the counting of the counting relay C and the setting of the device M_s is detected by the gate As. Likewise, coincidence of the counting of the device C with the setting of the device M_r is detected by the gate Ar.

The gate As drives a set coil S of the memory relay Obj, while the gate Ar drives a reset coil R of the memory relay Obj. In case a plurality of control channels are required, a corresponding plurality of devices M_s and M_r are provided to cover all channels.

When the apparatus thus has a plurality of functions, one of the channels can be utilized for selection control of the two pulse generators Osc₁ and Osc₂ housed in said programming apparatus; such loop is indicated with dotted line as mentioned above. One of such plural channels can also be utilized for returning the whole programming apparatus. In the figure is shown an example of such control loop so connected that the output from the gate Ar is fed through a return control device Rr to the relay C for having it returned. Such return control can be accomplished not only by the set program but also manually or by an exterior signal and for this purpose a return control device Sw is connected to the reset coil R and the relay C.

The basic concept of the present invention has been discussed through description of the construction and functions of an embodiment shown in FIG. 1. However, it is to be pointed out that FIG. 1 is only for such particular purpose as to illustrate the basic concept of the present invention and the explanation given above with reference to FIG. 1 can be somewhat different in terms of expression from the detailed explanation given below, especially concerning the logic circuit.

2. Program Setting Device

The outline of the present invention thus being discussed with reference to FIG. 1, the whole apparatus will be described in more detail by dividing the apparatus into the program setting device and the program control device. First, in this subsection, the program setting device, generally referring to the counting relay C, the setting devices M_s and M_r and the memory relay Obj, will be described in detail.

FIG. 2 is a circuit diagram showing the set-driving setting device MS of the program setting device of an embodiment of the present invention, while FIG. 3 is a circuit diagram showing the reset system provided cooperatively with the circuit shown in FIG. 2. Each of memory relays provided in a plurality of channels is so controlled that it is set-driven at the first set timing and then reset-driven at the second set timing.

Referring first only to FIG. 2, an embodiment of the abovementioned program setting will be described in detail in the following. The circuit shown in FIG. 2 is similar to that of FIG. 2 in structure as well as function and hence the understanding of FIG. 2 will facilitate that of FIG. 3. Now referring to FIG. 2, the program setting device for the set-driving is characterized by the fact that a rough counting relay C₁₀, a rough counting-channel matrix device MS₁₀ attached thereto, set coils S of the memory relays provided in each channel, a

rough counting-channel matrix device MS_1 and a fine counting relay C_1 are connected in this order between a power source $+V$ and the ground GND . The rough counting relay C_{10} corresponds, for instance, to a 10th digit counter and makes step up or count up on arrival of a 10th digit input pulse P_{10} (or count up on arrival of every 10th input pulse P_1), providing the output successively at terminals 0, 1, 2 ..... 9. Similarly the fine counting relay C_1 corresponds, for instance, to a unit digit counter and makes count upon arrival of a unit digit input pulse P_1 , providing the output successively at terminals 0, 1, 2 ..... 9.

The setting matrix devices MS_{10} and MS_1 may be of the same construction and the column contacts correspond to the abovementioned counting relay terminals and the row contacts to the plural channels. In the embodiment shown in FIG. 2 is shown for simplicity of illustration an example of only 15 channels Ch_1 , Ch_2 ..... Ch_{15} . Also in the embodiment shown are provided channels Cho and Che , which, as will be described in detail later, are used for selection control of the abovementioned pulse generators Osc_1 and Osc_2 and selection control of pulse sources provided inside and outside the apparatus. The setting matrix devices are so designed that any one point of intersection for each channel can be closed adjustably between row and column contacts. For each channel, one of the set coils ($S_1, S_2, \dots, S_{15}$) and a backward current blocking diode d_2 are connected between the two matrix devices MS_{10} and MS_1 .

FIG. 3A shows an illustration of a typical embodiment of such a memory relay. The set coil S is wound together with the reset coil R on a core CO to form a memory relay Obj . Upon energization of the set coil S the core CO is magnetized and the resultant residual magnetism keeps an armature A attracted to the core CO . The memory relay is thus set-driven. Upon energization of the reset coil R the core CO is demagnetized and the armature A is urged to a returned state by means of a spring and remains returned. Thus the memory relay Obj is reset-driven.

In operation, it is now assumed that for the channel Ch_1 setting is made for timing of count 23 for controlling of the set coil S_1 . The intersection for the channel Ch_1 and the terminal 2 of the rough setting matrix device MS_{10} is then closed and the intersection of channel Ch_1 and the terminal 3 of the device MS_1 is closed. Similar setting is made with respect to the other channels. The set coil S_1 for the channel Ch_1 is energized when the counting relays C_1 and C_{10} make the count up to reach a count corresponding to 23. The same applies to other channels.

As the programming apparatus has a plurality of channels, a circuit leading from the device MS_{10} to the device MS_1 through a certain channel, then back to the device MS_{10} through another channel and also back to the device MS_1 through still another channel could be formed at a certain timing. This means the possibility of the so-called "short circuit" which can give cause for an erroneous action not in accordance with the set program. The backward current blocking diode d_2 is therefore provided to prevent this phenomenon.

As may be apparent from the foregoing description, the adoption of two sets of counting relays and matrix devices and of the described mode of circuit connection enables a simplified circuit and markedly finer subdivision of the set timing. In the illustrated example set-

ting is possible for $10 \times 10 = 100$ counts or steps. If this setting capacity were to be accomplished with the use of a single counting relay and matrix device, the program device would have been liable to be highly complex and expensive.

In the embodiment shown in FIG. 2 indicator lamps L_{10} and L_1 are connected together with the backward current blocking diodes d_1 between the counting relays C_{10} and C_1 and the power source through terminals 0, 1, 2 ..... 9 so that the stepping up of count can be observed visually.

Additional channels Chc and Che are utilized for controlling the operation of the programming apparatus by the set program itself. For instance, the programming apparatus can be made multi-functional by providing the possibility of controlling the pulse repetition frequency or synchronism of input pulses P_1 and P_{10} by the set program. For this purpose the channel Chc is utilized for selection control of the generators Osc_1 and Osc_2 shown in FIG. 1, while the channel Che is utilized for selection control of the pulse sources, one of which is built in the programming apparatus and the other is provided outside the apparatus.

The circuit shown in FIG. 3 is used for reset driving 25 of the reset coil R of the memory relay Obj , whereas the circuit shown in FIG. 2 is used for set control of the set coil S . The circuit shown in FIG. 3 is substantially the same as that shown in FIG. 2 and hence, for avoiding repetition of detailed description, the corresponding 30 parts of these two circuits are referred to by the same or similar reference characters (For instance, S for the set side in FIG. 2 and R for the reset side in FIG. 3 are used.). In the following description emphasis is placed only on the major difference between them. In FIG. 3 35 the count indicating lamp circuit is omitted to avoid duality.

The circuit shown in FIG. 3 has an additional channel Chr , which is used for resetting the counting relays of the whole programming apparatus according to the set 40 program. At the same time it is also necessary to reset the memory relay. For this purpose there are connected between power source $+V$ and ground GND a switch Sw_1 , the backward current blocking diodes d_4 , and switch Sw_2 in series. The switches Sw_1 and Sw_2 can 45 also be operated manually.

3. Program Control Device

In the following control of the whole programming apparatus of the present invention will be described. For this purpose FIGS. 4A and 4B show the left half 50 and right half of the circuit diagram of the control system of the apparatus shown in FIG. 1, respectively, and FIGS. 5 and 6 show the set-driving program setting device and the reset-driving program setting device, respectively, in somewhat simplified manner and together with a part of the circuits related to the above-mentioned program control device.

Now referring to FIGS. 4A and 4B, the control device is connected through a power source switch Pow Sw inserted in a bus Bus to a power source PS and between the bus Bus and the ground GND are connected 60 relays for various control functions, relay contacts and coils of the abovementioned memory relays. As regards these relays, as a rule, a normally open contact or an a -contact is designated by adding a subscript a to the reference character for relay (also a serial number when a plurality of contacts are provided) and a normally closed contact or a b -contact by adding a sub-

script *b* to the reference character for relay (also a serial number when a plurality of contacts are provided).

At the right end of the control circuit is provided a direct current generating device composed of a transformer Trans and a rectifier Rect which are connected to the circuit over terminals A and B, and the direct current taken out of terminals C and D is used as a DC source for the circuits shown in FIGS. 5 and 6. In the following is described the structure and operation of the control device.

a. Counting Operation of Counting Relay C

As mentioned above, the counting relay C receives pulses from either of the pulse generators Osc_1 and Osc_2 (which are to be described in more detail later). This counting relay, however, can alternatively be connected to receive pulses from an exterior pulse source or a manual pulse source. In any case the pulse is fed to the coils of counting relays C_1 and C_{10} for stepping operation.

As a result of this first stepping the movable contact is moved off terminal O and a relay X_0 is turned off and the stepping operation is continued with a contact X_{0b2} remaining on until the movable contact comes in contact with a terminal 9, at which time a relay X_{10} is turned on and is self-hold on as a function of a contact X_{10a} , which causes a carry over to a relay C_{10} or makes the relay C_{10} step up and the relay C_1 return. In FIG. 6 the illustration of the relays X_0 and X_{10} and contacts X_{0b2} and X_{10a} required for this stepping operation is omitted for the sake of convenience. This carry over stepping operation by a series connection of two counting relays is well known to those skilled in the art.

b. Selection of Pulse Sources

When the manual switch Sta for selection of pulse source to the built-in pulse generator is turned on, the relay X_1 is turned on, contact X_{1a} is closed and either one of on-delay timers T_1 and T_2 corresponding to the pulse generators Osc_1 and Osc_2 , respectively, is turned on. The timers T_1 and T_3 and relay X_2 and their contacts form the pulse generator Osc_1 , while the timers T_2 and T_3 and relay X_2 and their contacts form the pulse generator Osc_2 .

In more detail, the delay time of the timer T_1 is chosen to be the pulse interval T_1 of the pulse generated by the pulse generator Osc_1 and the delay time of the timer T_2 is chosen to be the pulse interval T_2 of the pulse generated by the pulse generator Osc_2 . The delay time of the timer T_3 is chosen to be the pulse width T_3 of the pulses generated by both generators Osc_1 and Osc_2 . When the contact X_{1a} is closed, either timer T_1 or T_2 is turned on, as the case may be, and after a lapse of the time period T_1 or T_2 the contact T_{1a} or T_{2a} is turned on, which makes the current flow through the counting relay C_1 . At the same time the timer T_3 is turned on and after a lapse of the time period T_3 the contact T_{3a} is turned on, at which time the relay X_2 is instantaneously energized and the contact X_{2b} is instantaneously opened. Thus the timer T_1 or T_2 is returned to the initial state and the abovementioned operation is repeated thereafter.

Assuming that the pulse generator Osc_1 is in operation, for example, the pulse is generated as a result of the fact that the contact T_{1a} is turned on or off with co-operation of the timers T_1 and T_3 and the relay X_2 , resulting in application of the pulse to the coil of the counting relay. Similarly in case of the pulse generator Osc_2 , the contact T_{2a} is closed intermittently by the tim-

ers T_2 and T_3 and the relay X_2 and the pulse thus generated is given to the coil of the counting relay. The contact X_{1b} is then kept off, which disables the terminal Out_2 which is closed by an exterior signal fed from an exterior pulse source. Thus, with the exterior pulse source disabled, either of the inside pulse generators Osc_1 and Osc_2 is in operation.

It is to be pointed out that a one-shot multivibrator may be used in place of a combination of the relay X_2 and the timer T_3 . It is also to be pointed out that preferably a variable setting timer is used as the timer T_1 . Employment of such a variable setting timer permits manual setting of any pulse repetition frequency of the pulse generated by the generator.

The selection of pulse sources Osc_1 and Osc_2 is done as follows. When a selection switch $Fast$ is manually turned on, the set coil XS_{16} is turned on at the preset count or step, at which time the contact XS_{16a} is closed to turn on a relay X_6 , which is then self-hold on by co-operation of the contact X_{6a} . At a later preset step the reset coil XR_{16} is turned on and at the same time the contact XR_{16b} is turned off, which makes the relay X_6 turn off. Before relay X_6 is turned on, the circuit including the timer T_1 is completed and after the relay X_6 is turned on the circuit including the timer T_2 is completed. Thus, either of the generators Osc_1 and Osc_2 is selected. Since the pulse generators Osc_1 and Osc_2 are different in frequency of the generated pulse, it is apparent that the count up or step up speed of the counting relays C_1 and C_{10} can be varied according to the program set by the programming apparatus. A switch Fex controlled by the exterior control pulse functions likewise.

When the switch Sta is turned off, the relay X_1 is turned off and contact X_{1a} is opened. This disables the circuits including the timers T_1 and T_2 and as a result the built-in pulse generators Osc_1 and Osc_2 are turned off. At the same time the contact X_{1b} is closed and the set coil C_1 is now energized by an exterior pulse signal generated by intermittent closing of the terminal Out_2 . When the terminal Out_1 being closed the exterior signal is turned on while the switch Sta is off the system operates in the same way as in case the switch Sta is turned on and the pulse source can be changed over to the built-in pulse generator by the control signal given to the terminal Out_1 being closed by the exterior signal.

If a switch which operates according to a set program is provided in parallel with the switch Sta and the terminal Out_1 , the selection of the inside and outside pulse sources is then possible also by the set program in addition to the described method of selecting the inside and outside pulse sources manually or by the exterior signal. The connection for such a purpose will be described in the following. The channel Che of the programming apparatus is used for such a purpose. The set coil XS_{17} is turned on at a given set position, resulting in closing of the contact XS_{17a} . The relay X_{00} is then turned on, resulting in closing of the contact X_{00a1} and the relay X_{00} is self-hold on. The contact X_{00a2} is closed and the relay X_1 is turned on, so that the changeover to the built-in pulse generators Osc_1 and Osc_2 is accomplished. Then at a certain set position the reset coil XR_{17} is turned on, resulting in opening of the contact XR_{17} . Accordingly the self-holding of the relay X_{00} is released and the relay X_1 is turned off. The changeover to the exterior pulse signal source is thus accomplished.

c. Return Operation

The programming apparatus of the embodiment shown of the present apparatus can be returned at a preselected step position either by the exterior signal, manual signal or according to a set program. For this purpose, the apparatus is provided with return coils RTC₁ and RTC₁₀ for returning the coils C₁ and C₁₀.

When the manual switch MR is turned on, the relay X₈ is turned on and self-hold on with closing of the contact X_{8a3}. The contact X_{8a1} is closed and the relay X₄ and the coil RTC₁ are turned on. Also the contact X_{8a2} is closed and the coil RTC₁₀ is turned on. Thus all counting relays C₁ and C₁₀ are reset to zero or returned. Simultaneously the contacts X_{8a4} and X_{8a5} shown in FIG. 6 are closed and the reset coils R (R₁, R₂, R₃ . . . R₁₅) of the memory relays are turned on for reset-driving the entire memory relay. On returning of the counting relay, the relay X₆ is turned on and the contacts X_{6b1} and X_{6b2} are opened, which releases the self-holding of the relays X₈ and X₁₀. At the same time the relay X₄ is turned on and the contact X_{4b} is opened for preventing possible closing of the circuit when the set step is passed through during return of the counting relay to zero. The contact X_{10b} connected in series with the contact X_{4b} is for the purpose of a similar operation required when the unit digit count is returned to zero in the process of carry over.

Now that, in the foregoing the procedure required for manual returning has been described, the procedure for returning according to set program by using the programming apparatus will be described in the following. The channel Chr is set in advance for a desired return program and hence the reset coil XR₁₈ is turned on at the said step position. Under this setting, the returning is accomplished according to the set program, the rest of the procedures being the same as in the case described above in conjunction with the switch MR being on. The similar return is possible by using the terminal Out₃ closed by the exterior signal.

4. Appearance of an Embodiment Apparatus

FIG. 7 shows an elevational view of the programming apparatus of an embodiment in accordance with the present invention and FIG. 8 shows a rear view of the apparatus shown in FIG. 7. Referring to FIG. 7, there may be seen the setting matrixes MS₁₀, MS₁, MR₁₀ and MR₁; the indication lamps L₁₀ and L₁; the manual switches MR and MS; the manual switch Sta for changing the pulse source to the built-in pulse generator; and the power source switch Pow Sw, arranged on the front panel. Referring to FIG. 8, there also may be seen the variable setting timer T₁; the terminals closed by the exterior signals Out₁, Out₂ and Out₃; common contacts CC, normally open contacts CA and normally closed contacts CB for fifteen memory relays, arranged on the rear panel. Further the power source PS is shown in a simplified manner connected to the power source terminal. Likewise three loads L₁, L₂ and L₃ are shown in a simplified manner connected between the common contacts CC and the normally open contacts CA of the memory relay for the channels 1, 2 and 3.

While specific preferred embodiments of the invention have been described, it will be apparent that obvious variations and modifications of the invention will occur to those of ordinary skill in the art from a consideration of the foregoing description. It is, therefore, desired that the present invention be limited only by the appended claims.

We claim:

1. Programming apparatus comprising:
means for generating pulses;
counting means for counting said pulses, said counting means comprising first and second counting relays for performing rough counting and fine counting of the pulses, respectively;
first setting means associated with said counting means and comprising a plurality of channels, each providing an output when counting reaches a preset count;
second setting means associated with said counting means and comprising a plurality of channels, each providing an output when counting reaches a preset count;
each of said first and second setting means comprising a rough setting portion for establishing a rough setting with respect to said first counting relay and a fine setting portion for establishing a fine setting with respect to said second counting relay;
a corresponding plurality of memory relays, each of said corresponding memory relays being actuated independently of said other memory relays to either of its first or second states in response to the outputs of the corresponding channels of said first and second setting means, respectively;
said pulse generating means having a pulse repetition frequency of the output thereof which is selectively variable;
means for controlling the pulse repetition frequency of said pulse generating means by the use of one of said plurality of memory relays;
as to each of said first and second setting means, said first counting relay, said rough setting portion thereof, said fine setting portion thereof, and said second counting relay being connected in series in the above-mentioned order; and
said memory relays being connected in series between said rough and said fine setting means of said series connection.
2. Programming apparatus in accordance with claim 1, which further comprises means for returning said counting means at a given time during the progress of the program.
3. Programming apparatus in accordance with claim 2, wherein said returning means is controlled in response to at least one of said plurality of memory relays to effect that return operation.
4. Programming apparatus in accordance with claim 1 in which diodes are connected in series with said memory relays for preventing a backward current flow therethrough.
5. Programming apparatus in accordance with claim 1, wherein said controlling means actuates the output of said pulse generating means to a first pulse repetition frequency in response to the first state of said memory relay and to a second pulse repetition frequency in response to the second state of said memory relay, respectively.

6. Programming apparatus in accordance with claim 1, wherein said pulse generating means comprises a pulse source provided internally of said apparatus and a terminal means for connection to a pulse source provided externally of the apparatus, and said apparatus further comprising means for selecting one of said internal pulse source and said external pulse source to be connected to said terminal means for supplying pulses therefrom to said counting means.

7. Programming apparatus in accordance with claim 6, wherein said means for selecting said pulse generating means is controlled in response to at least one of said plurality of memory relays.

8. Programming apparatus in accordance with claim 1, characterized in that said memory relays are driven to a set state by an output of said first setting means and to a reset by an output of said second setting means.

9. A programming apparatus comprising:
 pulse generating means having variable setting timer 10
 means for generating a train of pulses having a selectively variable pulse repetition frequency,
 rough and fine counting relays for counting said pulses,
 first rough and fine setting means associated with said 15 rough and fine counting relays, respectively, and having a plurality of channels, each of said channels providing an output when the count of said counting relays reaches a preset count,
 a plurality of memory relays corresponding to said 20 plurality of channels, each of said memory relays having a set coil and a reset coil,
 means for connecting said set coils in series with and between said first rough and fine setting means of said respectively corresponding channels, 25
 means for connecting said reset coils in series with and between said rough and fine setting means of said respectively corresponding channels,
 diodes connected in series with said set and reset coils for preventing backward current flow there- 30 through, and
 means for returning said counting relays and memory relays at a given time point during the progress of the program, said return operation of said returning means being controlled in response to at least 35 one of said plurality of memory relays, the pulse repetition frequency of said pulse generating means being selected in accordance with the state of one of said memory relays.

40

10. A programming apparatus comprising:
 pulse generating means having variable setting timer means for generating a train of pulses having a selectively variable pulse repetition frequency,
 rough and fine counting relays for counting said pulses,
 first rough and fine setting means associated with said rough and fine counting relays, respectively, and having a plurality of channels, each of said channels providing an output when the count of said counting relays reaches a preset count,
 a plurality of memory relays corresponding to said plurality of channels, each of said memory relays having a set coil and a reset coil,
 means for connecting said set coils in series with and between said first rough and fine setting means of said respectively corresponding channels,
 means for connecting said reset coils in series with and between said second rough and fine setting means of said respectively corresponding channels,
 diodes connected in series with said set and reset coils for preventing backward current flow therethrough, and
 means for returning said counting relays and memory relays at a given time point during the progress of the program, said return operation of said returning means being controlled in response to at least one of said plurality of memory relays, the pulse repetition frequency of said pulse generating means being selected in accordance with the state of one of said memory relays.

UNITED STATES PATENT OFFICE
CERTIFICATE OF CORRECTION

Patent No. 3,786,239

Dated January 15, 1974

Inventor(s) Noboru Sano and Yoshihide Bando

It is certified that error appears in the above-identified patent and that said Letters Patent are hereby corrected as shown below:

Column 10, line 1, issued claim 1 should read as follows:

1. A programming apparatus, comprising:
means for generating pulses;
means for counting said pulses, said counting means comprising first and second counting relays, one thereof performing rough counting and the other thereof performing fine counting of the pulses;
first setting means associated with said counting means for providing an output when the count of said counting means reaches a preset count;
second setting means associated with said counting means for providing an output when the count of said counting means reaches a preset count; and
memory means having first and second states and being responsive to the output of said first setting means to be set to said first state, and to the output of said second setting means to be set to said second state, said memory means comprising a plurality of memory relays, each of said memory relays being driven to a set state by an output of said first setting means and to a reset state by an output of said second setting means,
each of said first and second setting means comprising a rough setting portion for establishing a rough setting with respect to said first counting relay and a fine setting portion for establishing a fine setting with respect to said second counting relay,
as to each of said first and second setting means, said first counting relay, said rough setting portion thereof, said fine setting portion thereof, and said second counting relay being connected in series in the above-mentioned order, and
said memory relays being connected in series between said rough and said fine setting means of said series connection.

UNITED STATES PATENT OFFICE
CERTIFICATE OF CORRECTION

Patent No. 3,786,239 Dated January 15, 1974

Inventor(s) Noboru Sano and Yoshihide Bando Page - 2

It is certified that error appears in the above-identified patent and that said Letters Patent are hereby corrected as shown below:

Add new claim 5 as follows:

5. Programming apparatus as claimed in claim 1, wherein said pulse generating means has a pulse repetition frequency of the output thereof which is selectively variable, and there is included means for controlling the pulse repetition frequency of said pulse generating means by the use of one of said plurality of memory relays.

Issued claim 5, column 10, line 48, change the numbering to issued claim 6; line 49, column 10, change the dependency from claim 1 to claim 5.

Issued claim 7, column 11, line 1 change the numbering to claim 8; line 2, change the dependency from claim 6 to claim 7.

Issued claim 8, column 11, line 5, change the numbering to claim 9.

Issued claim 9, column 11, line 9, change the numbering to claim 10.

Signed and sealed this 9th day of July 1974.
